UNITED STATES PATENT OFFICE.

HENRY B. NICHOLS, OF PHILADELPHIA, PENNSYLVANIA.

PORTABLE RIVETING APPARATUS.

No. 826,522.

Specification of Letters Patent.

Patented July 17, 1906.

Application filed July 19, 1904. Serial No. 217,381.

To all whom it may concern:

Be it known that I, HENRY B. NICHOLS, of Philadelphia, in the county of Philadelphia and State of Pennsylvania, have invented a new and useful Improvement in Portable Riveting Apparatus, of which the following is a full, clear, and exact description, reference being had to the accompanying drawings, which form a part of this specification.

10 My invention has relation to portable riveting apparatus for use in riveting rail-joint plates to track-rails in the track, and is designed to provide apparatus of this character in which the power-operated riveting tool is so arranged as to be perfectly within the control of the operator or operators, so that it may be easily shifted from one rivet to another and from one joint to another with little manual effort. To this end I mount 15 the apparatus upon a movable vehicle which can be drawn by horses or other animals or propelled after the manner of an automobile along and parallel with the track to which the joints are to be applied. On this vehicle 20 I mount the apparatus for supplying the power to the riveter. This power is preferably compressed air supplied by one or more air-compressors drawn by suitable motors. I also provide the vehicle with a fixed table, 25 roller-mounted upon which is a horizontal crane arm or jib, which is preferably arranged to turn through an entire circumference. Mounted to travel on this arm or jib is a carriage from which the riveter is flexibly suspended, preferably through the medium of a differential hoist block or wheel. The gearing which effects the movement of the crane-arm as well as that which effects 30 the movement of the carriage is so arranged 35 that it can be actuated by the riveter operator without leaving the riveter. To counterbalance the weight of the crane-arm and riveter, the air compressor or compressors with their motor or motors are mounted to 40 be adjusted transversely of the vehicle.

45 My invention also consists in the novel construction, arrangement, and combination of parts, all substantially as hereinafter described, and pointed out in the appended 50 claims, reference being had to the accompanying drawings, in which—

Figure 1 is a plan view of the apparatus embodying my invention, and Fig. 2 an end elevation of the same.

55 The numeral 1 designates the body por-

tion of the movable vehicle upon which the apparatus is mounted, and 2 the air-compressors and their motors, which supply air to the tanks or reservoirs 3. These motors may be electric motors whose current-supply is obtained by a temporary connection with the conductors of the railway in connection with which the apparatus is being used or they may be steam or gasoline motors of any approved type.

4 designates an elevated circular table erected on the vehicle-body above the compressors 2 and upon which is mounted on the center 5 and rollers 6 the inner end portion of the crane arm or jib 7. Said table is 70 provided with an internal gear 8, engaged by a gear-wheel 9 on a vertical shaft 10, journaled to said arm, and also carrying a bevel-wheel 11, which is engaged by a corresponding wheel 12 on the inner end of a horizontal shaft 13, which is also journaled upon the said arm. Shaft 13 also carries a worm-wheel 14, meshing with a worm 15 on a shaft 16, which also carries a chain-wheel 17. By means of a depending chain or cord 18, working over this wheel, the control of the gearing is placed within reach of the operator at the pneumatic riveter 19. This riveter is of any approved type, being supplied with air from the reservoirs 3 by a flexible pipe or 80 hose 20, supported on the crane-arm. The riveter is flexibly suspended from the hoist 21, which is in turn suspended from a carriage 22, which is mounted to travel on the flanges of the arm 7. This carriage is propelled through suitable gearing 22*, actuated by a chain-wheel 23 and chain 24. It will be readily seen that by means of the chains 18 and 24 and the chain 25 of the hoist 21 the riveter is perfectly within the control of the operator. The point 26 of suspension of the riveter is as nearly as possible the point of its center of gravity, whereby its manipulation is rendered extremely easy. In order to counterbalance the weight of the arm 7 and of the riveter, the compressors 2 with their motors are movably mounted on slides 27, upon which they may be adjusted by the screw-shafts 28.

29 29' designate stoves for heating the rivets. These stoves may be supplied with air by means of a pipe 30, leading from the reservoirs 3, or by a motor-driven fan located in front of the air-compressor.

The crane can be moved upon its table, so 110

as to be projected from either side of the vehicle and at any angle thereto as may be most convenient for the work in hand.

5 While I have shown the vehicle as adapted to be drawn by horses or other animals, it is obvious that it may be propelled by any suitable power.

10 The apparatus may be changed in details without departing from the spirit and scope 10 of my invention. Hence I do not wish to be limited to the particular embodiment thereof which I have herein shown and described.

15 Having thus described my invention, what I claim as new, and desire to secure by Letters Patent, is—

1. In a portable riveting apparatus, the combination of a vehicle, a horizontal, circularly-movable crane-arm carried by the vehicle, a riveting device suspended from said 20 arm, gearing for actuating said arm to change its position and means for actuating said gearing from the neighborhood of the riveter.

2. In portable track-working apparatus, the combination of a vehicle, a horizontal 25 circularly-movable crane-arm carried by the vehicle, gear for changing the position of the said arm, a carriage mounted to travel on the said arm, gear for actuating said carriage, a tool suspended from the carriage, and means 30 whereby both the said gears may be operated from a position adjacent to the tool.

3. In portable track-working apparatus, the combination of a vehicle, a horizontally- 35 movable crane-arm mounted thereon, gear for changing the position of the said arm, a carriage mounted to travel on the said arm, gear for actuating said carriage, a tool flexibly and adjustably suspended from said carriage, and means for actuating both of the 40 said gears and also for adjusting said tool.

4. In apparatus of the character described, the combination with a supporting-vehicle,

and a power-generating machine mounted thereon, of an extended horizontal crane-arm also carried by the said vehicle, and means for 45 adjusting the position of said power-generating machine to counterbalance the weight of said arm in its different positions.

5. In apparatus of the character described, the combination with a supporting-vehicle, 50 of a movable tool-carrying arm or jib mounted on said vehicle, a power-operated tool carried by the said arm, a power-generating machine carried on the vehicle, and means for adjusting the position of the said machine on 55 the vehicle to counterbalance the said arm in its different positions.

6. In a portable riveting apparatus, the combination of a vehicle, an elevated circular table carried by the vehicle, a horizontal 60 crane-arm mounted upon and geared to the said table, a carriage mounted to travel on the said arm, a hoist suspended from the said carriage, a power-actuated riveter suspended from the said hoist, gearing for actuating the 65 said crane-arm and also the carriage, and means adjacent to the riveter for controlling said gearing.

7. In a portable riveting apparatus, the combination of a vehicle, a horizontally- 70 movable crane-arm carried by the vehicle, a riveting device suspended from said arm, gearing for actuating the arm to change its position, means for actuating said gearing from the neighborhood of the riveter, and 75 means for counterbalancing the weight of said arm and its suspended riveting device in the different positions thereof.

In testimony whereof I have affixed my signature in presence of two witnesses.

HENRY B. NICHOLS.
